UNITED STATES PATENT OFFICE.

VICTOR R. KOONTZ, OF WAYNESBORO, PENNSYLVANIA, ASSIGNOR TO VICTOR TOOL COMPANY, OF WAYNESBORO, PENNSYLVANIA, A CORPORATION OF PENNSYLVANIA.

COLLAPSIBLE TAP.

1,209,306.

Specification of Letters Patent. Patented Dec. 19, 1916.

Application filed March 3, 1916. Serial No. 81,867.

To all whom it may concern:

Be it known that I, VICTOR R. KOONTZ, a citizen of the United States, residing at Waynesboro, Franklin county, and State of Pennsylvania, have invented and discovered 5 certain new and useful Improvements in Collapsible Taps, of which the following is a specification.

The present invention relates to automatically collapsible taps for cutting interior threads, and consists in the combinations and arrangements of elements hereinafter described and particularly set forth in the accompanying claims.

15 The invention has for its purpose to provide a tap with means for adjustably setting the bits, or chasers, whereby the working diameters thereof may be selective at will, and having a locking device for securely holding the cutters during the 20 threading operation, and which device is automatically released, through engagement with the work, to collapse the bits.

A further purpose of the invention is to 25 produce a tool of this character which may be operated in a simple and easily performed manner, and wherein the bit adjusting, releasing, and collapsing devices will in no manner interfere with the use of the 30 tool under ordinary working conditions.

The invention is shown by way of illustration in the accompanying drawings, wherein—

Figure 1 is an elevational view of the tool, 35 Fig. 2 a longitudinal sectional view thereof, Fig. 3 an end elevational view, Fig. 4 a horizontal sectional view, Fig. 5 a transverse sectional view, Fig. 6 a transverse sectional view taken through the latch, Fig. 7 an elevational view of the lever locking device 40 and release therefor, Fig. 8 a longitudinal sectional view of a modified form of lever releasing device, Fig. 9 a longitudinal sectional view of a further modified construction of the tool, and Fig. 10 a sectional view 45 of the bit end thereof taken at right angles to Fig. 9.

The tool comprises a stock 1 having radial slots 2 at one end thereof receiving the cutters or bits 3 that are carried by the tubular head or plunger 4 that has movement within said stock. The several bits are formed, each on one face, with a diagonally disposed groove 5, that is engaged by a complementary shaped tongue 6 on the head-piece

of the plunger 4, after the manner shown in Figs. 4 and 5. With this arrangement it will be seen that any lateral movement of said member 4 will cause a corresponding radial movement of the several bits 3, thereby collapsing the bits or setting the same for determining their working diameter.

The bit carrying member 4 is normally under tension to collapse the bits by a spiral spring 7 located within the stock 1 and having screw engagement with the reduced end 8 of the member 4 which is threaded for this purpose. Said spring is anchored to the stock at its opposite end by means of a bushing 9, likewise having screw engagement therewith, and said bushing is adapted to be adjusted by a screw bolt 10 having its head 11 fitting flush within the end of the stock 1.

The plunger 4 is automatically released to collapse the bits through the sliding movement of a collar mounted on the stock and adapted to engage with the piece being threaded when the desired depth of thread has been cut. Said collar consists of two parts, to wit: an inner sleeve 12 mounted on the stock and an outer sleeve 13 mounted on the inner sleeve and adjustable relatively thereto. The sleeve 12 is formed with a slot 13^a that engages with a key or rib 14 formed in the stock to hold the sleeve against angular movement, and said sleeve 13 is slotted at 16 to receive the pair of bolts 17 carried by the inner sleeve 12 and which secures the two sleeves together forming the collar. The two sleeves 12 and 13 are slotted in alignment, as at 18 (see Figs. 2, 6, and 7), to allow for movement of the bit setting lever 19 that is fulcrumed at 20 on the stock, and said lever passes through the slot 21 formed in the plunger and engages to operate said plunger through a stud 22 that is located within a suitably formed recess 23 in the head of the plunger.

The several bits are held in working position by the lever 19 through the instrument of a latch that is automatically released to collapse the bits by the sliding collar's engagement with the work. The latch consists of an arcuate block or bolt 24 (see Figs. 6 and 7) that works within a suitable channel-way 25 formed in the face of the stock, and is normally held in position across the path of the lever 19, to wit: the slots 18, by a spring 26. Said spring is located within

an elongated recess formed in the bolt (see Figs. 4 and 6) and is anchored by a stud or pin 27 having a curved arm 28^a passing through the coils of the spring in the manner shown in Fig. 6. The bolt or latch 24 is thereby normally held to engage the lever 9 through the spring 26, and a pin 28 carried by said bolt works within the cam slot 29 formed in the sleeve 12; and by the sliding movement of said sleeve, the bolt 24 is withdrawn through the pin and slot engagement (28 and 29), as will be understood. The sleeve 13 is adjustably mounted with respect to the sleeve 12, *i. e.*, by the slots and bolts 16 and 17, and may therefore be set to release the latch for collapsing the bits at the desired depth of thread cutting.

When the shape of the part to be threaded with the tap is such as to prevent the use of the trip collar, as, for instance, the tapping of a hole which is closed by a solid bottom wall, it is contemplated to use a trip pin, as shown in Fig. 8, instead of the trip collar. With this arrangement the head 30 of the stock is enlarged and bored to receive the pin or plunger 31 that is formed with a shank 32 having a cam slot 33 receiving the pin 28 of the sliding bolt 24. An adjusting screw 34 provides the contact member for the pin 31 to engage with the work, and by adjusting said screw, the bits may be collapsed at the point desired. A spring 35 is located within a chamber 36 formed in the pin 31, and engages with said pin and the stock to normally hold the former in operative position.

The several bits may be set for working at different diameters by means of a screw 37 in the head of the plunger 4 and contacting with the stud 22 that engages with the lever 19; and said stud is slotted, as at 38, to receive said lever. The head-piece 39 of the tool is centrally apertured, as at 40, giving access to the adjusting screw 37 for varying the angular relation between said lever and the bit carrying plunger. The degree of throw, or angle of action of the lever is thereby regulable for radially projecting the bits 3 to the extent desired.

50 In lieu of the arrangement just disclosed for setting the bits, it is contemplated to employ the device shown in Figs. 9 and 10, and in which case the lever 19 is fulcrumed at 20 to a sleeve 41 which is adjusted on the stock 1 by a collar 42 screw-threaded on said stock. In this instance the bit carrying member 43 is engaged directly by the lever at the point 44, and the lever is adapted to be released by a latch operated from the collar slidably mounted on the sleeve 41, as in the former instance. In this construction the stock 1 is of less diameter than in the former case, and likewise the plunger 43, retraction spring 7, and their associated parts are correspondingly reduced in size.

The shiftable fulcrum for the lever 19 in this case allows for regulating the throw of the plunger 43, as will be seen from an inspection of Fig. 9.

It is obvious that those skilled in the art may vary the details of construction and arrangement of parts without departing from the spirit of my invention, and therefore I do not wish to be limited to such features except as may be required by the claims.

What I claim as new and desire to secure by Letters Patent, is:

1. In a collapsible tap the combination of a stock, a bit supporting member movably mounted in the stock, bits carried by said member, a spring engaging said member and operable to collapse the bits, a lever for moving said member to set the bits, a device for holding said lever to secure the bits in set position, means for automatically actuating said device to release the lever, and means mounted wholly on the bit supporting member engaging with said lever for determining the working diameter of said bits, substantially as set forth.

2. In a collapsible tap the combination of a stock, a bit supporting member movably mounted in the stock, bits carried by said member, a spring engaging said member and operable to collapse the bits, a lever fulcrumed on the stock and engaging said member to set the bits, a latch for holding said lever to secure the bits in set position, a slideable member carried by the stock automatically operable to move said latch and release the lever, and adjustable means mounted wholly on said bit supporting member engaging with said lever for determining the working diameter of said bits, substantially as set forth.

3. In a tap the combination of a stock, a bit supporting member mounted in the stock, bits carried by said member, a lever fulcrumed on the stock, a stud mounted in said member engaging with the lever for setting the bits, and a screw adjustably mounted in the member engaging with said stud for determining the working diameter of the bits, substantially as set forth.

4. In a collapsible tap the combination of a stock, a bit supporting member mounted in the stock and formed with a slot therethrough, bits carried by said member, a lever fulcrumed on the stock and passing through said slot, a stud adjustably mounted in the member and engaging with said lever for setting and determining the working diameter of said bits, a latch working within a groove in the face of the stock for holding said lever, and a sleeve adjustably mounted on the bit operable to actuate said latch to release the lever and collapse the bits, substantially as set forth.

5. In a collapsible tap the combination of

a stock, a plunger movably mounted in the stock, bits carried by the plunger, means for retracting the plunger to collapse the bits, a lever engaging with the plunger to set the bits, a latch mounted on the stock adapted to engage the lever and hold the bits in set position, and a collar mounted on the stock having a cam slot engagement with the latch operable to release the lever and collapse the bits through said plunger, substantially as set forth.

6. The combination with a collapsible tap having a movable member carrying the bits and retracting means therefor, of a fulcrumed lever for setting the bits, a latch associated with the lever for holding the bits in set position comprising a slidable bolt, a spring normally holding the bolt in engagement with the lever, and means for effecting 20 the automatic release of said bolt, substantially as set forth.

7. In a collapsible tap the combination of a stock, a plunger mounted in the stock, bits carried by the plunger, means for retracting 25 the plunger, a lever fulcrumed on the stock engaging with the plunger for setting the bits, a collar slidably mounted on the stock and having a slot receiving said lever, a slideable bolt mounted within the face of the 30 stock and operable to project across the path of the lever and lock the same, and a pin carried by said bolt having a cam slot engagement with said collar whereby to actuate said bolt to release the lever for collapsing 35 the bits, substantially as set forth.

8. In a collapsible tap the combination of a stock, a plunger mounted in the stock, bits carried by said plunger, a member fixed to the stock, and a retraction spring having 40 screw engagement at its respective ends with said fixed member and the plunger, substantially as set forth.

9. In a collapsible tap the combination of

a stock, a plunger mounted in the stock and having a threaded portion, bits carried by 45 the plunger, a threaded member adjustably mounted in the stock, and a spiral retraction spring for the plunger having screw engagement with said threaded members, substantially as set forth.

50

10. In a collapsible tap the combination of a stock, a plunger mounted in the stock and having a threaded portion, bits carried by the plunger, a threaded bushing mounted in the plunger, a spiral retraction spring for 55 the plunger having screw engagement with said threaded members, and a bolt mounted on the plunger having screw engagement with said bushing for regulating the tension on said spring, substantially as set 60 forth.

11. In a collapsible tap the combination of a stock, a tubular plunger mounted in the stock, bits carried by said plunger, a retraction spring for the plunger adjustably 65 mounted in the stock, a lever fulcrumed on the stock and engaging with said plunger to set the bits, an arcuate bolt mounted within the face of the stock and adapted to engage with and hold said lever, a pin 70 carried by said arcuate bolt, a sleeve slidably mounted on the stock having a cam slot engagement with said pin to move said bolt and effect the release of the lever, and a sleeve adjustably mounted on the first 75 named sleeve adapted to engage with the work and thereby actuate the bolt releasing sleeve, substantially as set forth.

In witness whereof I have hereunto set my hand and seal at Waynesboro, Pennsylvania, 80 this 9th day of February, A. D. nineteen hundred and sixteen.

VICTOR R. KOONTZ. [L. S.]
